(57) **CLAIM**

The ornamental design for an automotive fascia as shown and described.

DESCRIPTION

FIG. 1 is a top, front, left perspective view of an automotive fascia;

FIG. 2 is a bottom, front, left perspective view of the automotive fascia of FIG. 1;

FIG. 3 is a front view of the automotive fascia of FIG. 1; FIG. 4 is a rear view of the automotive fascia of FIG. 1; FIG. 5 is a right side view of the automotive fascia of FIG. 1;

FIG. 6 is a left side view of the automotive fascia of FIG. 1; FIG. 7 is a top view of the automotive fascia of FIG. 1; and, FIG. 8 is a bottom view of the automotive fascia of FIG. 1. The ornamental design which is claimed is shown in solid lines in the drawings. The broken lines of equal length dashes in the drawings depict portions of the automotive fascia that form no part of the claimed design. Broken lines formed by unequal length dashes (i.e., dash-dot) define bounds of the claimed design.
